UNITED STATES PATENT OFFICE.

EDWIN RUST DOUGLAS, OF GLENSIDE, PENNSYLVANIA.

METHOD OF FORMING SCREW-THREADS IN CYLINDRICAL METAL ARTICLES.

1,083,598.

Specification of Letters Patent.

Patented Jan. 6, 1914.

Original application filed May 4, 1911, Serial No. 624,979. Divided and this application filed November 27, 1911. Serial No. 662,677.

To all whom it may concern:

Be it known that I, EDWIN RUST DOUGLAS, a citizen of the United States, residing in Glenside, in the county of Montgomery, 5 State of Pennsylvania, have invented a new and useful Method of Forming Screw-Threads in Cylindrical Metal Articles, of which the following is a specification.

My invention consists of an improved 10 method of forming screw-threads in cylindrical metallic articles.

It further consists of such a method in which the metal of the article is crowded or drawn to form a raised screw-thread on one 15 side, only, of the material.

It further consists in exposing the surface to be threaded to a revolving screw-threaded tool.

It further consists in fully supporting 20 the side of the article which is to remain smooth while exposing the side to be threaded to the action of a revolving screw-threaded tool.

It further consists in exposing the article 25 to a revolving screw-threaded tool while rotating the axis of said tool in a circle eccentric to the latter and to the article.

It further consists in supporting the article and revolving it while exposing the side 30 of the same to be threaded to the action of a screw-threaded tool revolving at the same speed as or any even multiple of the speed of the article and in the same peripheral direction at the point of contact as the article 35 and rotating the axis of such tool in a circle eccentric to the latter and in a direction, opposite to that of the revolution of the article.

It further consists in other improved steps 40 as will be further set forth.

This application is a division of an application Serial No. 624,979, filed by me on the 4th day of May, 1911, which issued on the 5th day of December, 1911, as Letters 45 Patent No. 1,010,740, for a machine for threading sheet metal caps, in which is disclosed a machine in which my improved method may be carried out.

The annexed drawings and the following 50 description set forth in detail one mode of carrying out my method.

talities being but one form of means for carrying out such method.

In said annexed drawings—Figure 1 represents an axial section of one-half of a 55 machine in which my improved method is carried out. Fig. 2 represents an axial section of the other half of such machine. Fig. 3 represents a top plan view of said latter half of the machine. Figs. 4 and 5 represent axial sections on an enlarged scale of the threading tool and chuck and their surrounding parts, with said chuck illustrated in disengaged and actuating positions, respectively. Fig. 6 represents an elevation of the 60 threading tool and its coöperating parts. Fig. 7 represents a transverse section of the trunk within which the spindle of the threading tool is supported. Fig. 8 represents a diagram illustrating the progress of 65 the threading tool in cutting the thread in the cap. Fig. 9 represents an elevation of a member of the "Oldham" coupling. Fig. 10 represents an elevation of another member of such coupling.

Similar numerals of reference indicate corresponding parts in the figures.

Referring to the drawings, the reference numeral 1 indicates a bed upon which the several parts of the machine are supported. 80 A tubular spindle, 2, is journaled in a bearing, 3, at one end of the machine bed and in a bushing, 4, sliding in a bearing-bracket, 5, upon the bed, and said spindle is driven by suitable connection to the drive-mechanism of the machine. The bushing is provided with a cross-head, 6, having a transverse groove in its under side which is engaged by a head, 7, slideable in said groove and swiveled in an eccentric arm upon a vertical rock-shaft, 8, connected to be rocked from the drive-mechanism of the machine at predetermined intervals. A chuck, 9, of the dimensions of the article to be threaded, is secured upon the inner end of the spindle, 95 and a disk, 10, forms the bottom of the recess in said chuck and has a stem, 11, slideable in the axial bore of the tubular spindle and bearing against a rod, 12, which slides in the spindle and has a spring, 13, forcing 100 it outward. The end of the rod projects beyond the end of the spindle and will engage

a stop-bolt, 14, adjustably secured in a bracket, 15, upon the bed-frame when the spindle is moved outward, and said rod 12 will thus be held, and by the continued movement of the spindle the rod, stem and disk push the article out of the recess in the chuck.

The chuck and its bottom disk are removable, so that chucks of various sizes and shapes may be used, according to the size and shape of the article to be threaded. A trunk, 16, is journaled in bearings, 17, upon the machine-bed, with its end opposed to the chuck and in axial alinement with the same and its spindle. Said trunk has a radial arm, 18, provided with a handle, 19, for rocking it, and adjusting-screws, 20, are threaded in ears, 21, upon one of the bearings and serve to adjust and secure the arm and trunk in whatever position they may be rocked. The trunk has an eccentric bore, 22, in which a sleeve, 23, is journaled, and said sleeve has an eccentric bore, 24, in which a tubular shaft, 25, is journaled. The end of the bore in said shaft is formed into a tapering socket, 26, in which the tapering shank, 27, of a screw-threaded threading-tool, 28, is secured, the end, 29, of said tool being screwed into the end, 30, of a rod, 30, which fits in the bore of the shaft and has nuts, 31, and a washer, 32, upon its projecting outer end, which bear against the end of the tubular shaft and serve to draw the tapering tool-shank into its socket. A drive-shaft, 33, revolved from any suitable power-connection, is journaled in bearings, upon the machine bed, one, 34, of said bearings being illustrated in Fig. 3. Said drive-shaft carries a pinion, 34², which meshes with a transmission-pinion, 35, which again meshes with a cog-wheel, 36, upon the sleeve in the trunk. The drive-shaft carries a cog-wheel, 37, which meshes with a pinion, 38, keyed upon a bushing, 39, rotatable upon the sleeve in the trunk, and said bushing has a disk, 40, keyed upon it and formed with a diametrical groove, 41, in its outer face, into which engage two diametrically alined tongues, 42, upon the inner face of a disk, 43, having an enlarged central opening, 44, to admit of eccentric movement of said disk and the tubular shaft and rod. The outer face of said disk has two diametrically alined tongues, 45, at right angles to the former tongues, and said tongues engage a diametrical groove, 46, in a disk, 47, keyed upon the tubular shaft 25 and further secured by the washer and nuts upon the axial rod. A balance-wheel, 48, is secured upon the periphery of the inner disk. The coupling thus formed is the well known "Oldham" coupling and its operation is well known. A roller or button, 49, is jour-

naled upon a plate, 50, secured to the face of 65 the inner bearing for the drum. Two rollers, 51, are journaled upon the face of the inner bearing, below the threading tool, and the chuck may rotate and be supported from below upon said rollers when it is moved 70 inward to have the threading tool act upon the cap.

Cylindrical hollow articles may be threaded by my improved method whether such articles have closed or open heads and 75 whether such articles are flanged, as illustrated in the drawings or have plain side-flanges.

In practice, the article is placed in line with the chuck, as seen in Fig. 4, either 80 manually or by a feeding device, whereupon the chuck is moved toward the threading tool which will push the blank into the chuck. The outer periphery of the chuck will rest and revolve upon the chuck-supporting rollers, and, if the article is flanged, as illustrated in the drawings, the small button or roller will bear with its face against such flange and force the same against the face of the chuck. The chuck and the 85 threading tool rotate in the same direction and with the same rotative speed, or the tool may revolve at a speed of any even multiple of the rotative speed of the chuck, while the axis of the threading tool revolves in a circle 95 around a center eccentric to the axis of the chuck in a direction of revolution opposite to that of the chuck and at a considerably less speed. A satisfactory ratio of speeds has been found to be two hundred and forty 100 rotations per minute for the threading tool and chuck and twenty revolutions per minute for the axis of the tool.

The rotating threading tool crowds the metal of the rim of the article up between the threads, and as the chuck is rotated, the tool is brought into contact with the entire circumference of the article to be threaded, while the slower revolution of the tool in a circle eccentric to its axis of rotation gradually forces the tool into the metal, crowding it up between the threads of the tool to form the screw-threads. The outer side of the article remains smooth, as the article fits snugly in the chuck, so that the threads are not 115 corrugated through the thickness of the metal but are formed upon one side, only, by the drawing action of the threading tool.

The process of the formation of the screw-thread is diagrammatically illustrated in 120 Fig. 8, where the wall of the article is indicated by the letter A, the travel of the threading tool by a series of circle-segments in various styles of broken lines, and the circular and eccentric path of the axis of the 125 threading tool by a dotted circle B. The directions of movement of the respective parts are indicated by arrows, and the pre-

ferred number of revolutions per minute by the corresponding numerals. The circumference of the threading tool as it begins to act upon the article is indicated by two full-line circles, C', described by a radius, C, at about thirty degrees (30°) from the point where the tool cuts deepest, as indicated by a radius, D, and two dotted-line circles, D', and the tool leaves the periphery of the article at a point forty-five degrees (45°) from the radius, D, as indicated by a radius, E, and two dotted-line circles, E', described by the latter. As the threading tool and the article rotate in the same direction and at about the same speed, the metal of the article will be drawn or rolled up into the threads of the tool, and the latter will gradually bear deeper into the metal as it rotates and will thereupon be drawn away from the article by its eccentric revolution. The threading tool describes somewhat more than one revolution, so that the thread will be of substantially even depth, and, at the ratio of speeds above stated, the tool and chuck will make at least twelve rotations to each one revolution of the tool.

By the herein disclosed method, screw-threads are formed in hollow cylindrical articles upon one side, only, of the article, without deforming the other side, and without removing metal from the screw-threaded side.

Other modes of applying the principle of my invention may be employed for the mode herein employed. Changes may be made as far as instrumentalities and steps disclosed are concerned, provided the principles of procedure set forth respectively in the following claims are employed.

Having thus described my invention what I claim as new and desire to secure by Letters Patent is:—

1. The method of forming screw-threads in cylindrical metal articles, which consists in supporting and rotating such article, applying a screw-threaded rotating threading tool to the rotating article, and gradually forcing such tool into the periphery of such rotating article.

2. The method of forming screw-threads in cylindrical metal articles, which consists in supporting and rotating such article, applying a screw-threaded threading tool rotating at the same rotative speed as the article to the periphery of the same, and gradually forcing such tool into the periphery of such rotating article.

3. The method of forming screw-threads in cylindrical metal articles, which consists in supporting and rotating such article, applying a screw-threaded rotating threading tool to such rotating article, and revolving the axis of such tool in a circle eccentric to such axis.

4. The method of forming screw-threads in cylindrical metal articles, which consists in supporting and rotating such article, applying a screw-threaded threading tool rotating at the same or an even multiple of the rotative speed as the article to the periphery of the same, and revolving the axis of such tool in a circle eccentric to such axis.

5. The method of forming screw-threads in cylindrical metal articles, which consists in supporting such article and rotating it, applying a screw-threaded threading tool rotating at the same or an even multiple of the rotative speed and in the same peripheral direction as the article at the point of contact to the periphery of the article, and revolving the axis of such tool in a circle eccentric to such axis at a slower speed.

6. The method of forming screw-threads in hollow cylindrical metal articles, which consists in supporting the entire side of the same which is not to be threaded and rotating the article, applying a rotating screw-threaded threading tool to the surface of the article to be threaded, and gradually feeding such tool into the metal of the article.

7. The method of forming screw-threads in hollow cylindrical metal articles, which consists in supporting the entire side of the same which is not to be threaded and rotating the article, applying a rotating screw-threaded threading tool to the surface of the article to be threaded, and revolving the axis of such tool in a circle eccentric to such axis.

8. The method of forming screw-threads in hollow cylindrical metal articles, which consists in fully supporting the side of the article which is not to be threaded, applying a rotating screw-threaded threading tool to the side to be threaded, and feeding such tool into the metal of the article, thus crowding the metal forming the threads between the threads of the tool.

9. The method of forming screw-threads in hollow cylindrical metal articles, which consists in fully supporting the side of the article which is not to be threaded and rotating such article, applying a screw-threaded threading tool rotating at the same or an even multiple of the rotative speed and in the same peripheral direction as the article at the point of contact to the side of the article to be threaded, and revolving the axis of such tool in a circle eccentric to such axis and in a direction opposite to that of the article.

10. The method of forming screw-threads in hollow cylindrical metal articles, which consists in fully supporting the side of the

article which is not to be threaded and rotating such article, applying a screw-threaded threading tool rotating at the same or an even multiple of the rotative speed and in the same peripheral direction as the article at the point of contact to the side of the article to be threaded, and revolving the axis of such tool in a circle eccentric to such

axis in a direction opposite to that of the article and at a speed slower than that of the latter.
